Inventor

UNITED STATES PATENT OFFICE.

ELMER F. DORSEY, OF KANSAS CITY, KANSAS.

FOUNTAIN-BRUSH.

SPECIFICATION forming part of Letters Patent No. 615,063, dated November 29, 1898.

Application filed August 1, 1898. Serial No. 687,471. (No model.)

To all whom it may concern:

Be it known that I, ELMER F. DORSEY, a citizen of the United States, residing at Kansas City, in the county of Wyandotte and State of Kansas, have invented certain new and useful Improvements in Liquid-Supplying Devices for Brushes or Brooms; and I do hereby declare that the following is a full, clear, and exact description of the invention, so as will enable others to make and use the same, reference being had to the accompanying drawings, forming a part of this specification.

My invention has for its objects, first, the continuous supply of liquid to the interstices of a brush or broom while in use; second, the distribution of the liquid in the uniform direction of the length of the brush; third, the adjustment of the liquid-conductors to accommodate brushes of different sizes, and, fourth, the regulation of the flow of the liquid to the brush or broom from the liquid source of supply.

My invention consists in the novel construction and combination of parts, such as will be first fully described, and specifically pointed out in the claims.

In the drawings, Figure 1 is a view in perspective of a scrubbing-brush, showing my invention applied thereto, also showing the hollow liquid-conducting handle, the liquid-supply tank, and the flexible conductor of liquid connected with the tank and also with the handle and the check-valve. Fig. 2 is a front view in detail of the brush-clamping liquid-distributing pipes, showing the adjustable connecting-pipe and the perforations for deflecting the liquid. Fig. 3 is a vertical sectional view taken through the liquid-distributing and adjustable connecting-pipe. Fig. 4 is a sectional view of the check-valve at the end of the water-conducting handle, showing portions of the handle and flexible liquid-conductor. Fig. 5 is a view of an alternate liquid-distributing device applied to a broom. Fig. 6 is a view in perspective of the invention, with the check-valve lever extending between the operating-handles to the brush.

Similar letters of reference indicate corresponding parts in all the figures.

Referring to the drawings, A represents an ordinary scrubbing-brush, of which a is the

back of the brush and a' the bristles. Upon one longitudinal edge portion of the back a of the brush, which is relatively the forward edge, is a liquid-distributing pipe b, extending the length of the brush and closed at both ends by the removable plug b². In the side of pipe b which is near in position to the bristles a' are perforations b³, which are directed toward the interstices or the spaces between the separate fingers formed by the bristles. (See Figs. 2 and 3.) Upon the other edge portion of the brush is a pipe b of the same length as the former pipe b. With the side of each pipe, at one end of the brush A, is connected rigidly a clamping-plate c, which plates are bent over the edge of the brush and extended a short distance toward each other in the same plane as described by the back of the brush, and a portion c' of said plates extended outwardly and at right angles to the back of the brush, thus forming separate clamping-plates. Through the clamping-plates c' is extended a clamping-bolt c², upon one end of which bolt is a head and which bears upon one clamping-plate c', and upon the other end of said bolt is a thumb-nut c⁴, which bears upon the other plate c'. At the other end of the brush A and connected with the other end of the liquid-distributing pipes are clamping-plates which are precisely the same as the plates c c' and provided with a clamping-bolt, as described of the bolt c².

With one of the liquid-distributing pipes upon the forward edge of the brush, at a point equidistant from the clamping-plates c, is connected one end of a liquid-conducting pipe d, which extends a short distance from said pipe in the plane of the edge of the back a of the brush and is bent at d² and extended in the same plane as the said back a little over one-half the distance toward the opposing edge of the brush and telescopes with a short section of pipe d², which pipe extends a short distance past the line of the rear edge of the brush A and is connected with the pipe b upon said rear edge of the brush by means of a short branch pipe d³, extending from the under side portion of the pipe d² to the upper side portion of the distributing-pipe b. The forward end of the pipe d², which receives the pipe d, is screw-threaded externally, and upon said end is a nut d⁴, and upon the end of said

nut is connected rigidly an annular ring d^3 , which extends around the pipe d , and upon the nut, between said ring and the end of the pipe d^2 , is suitable water-tight packing. The 5 other end of pipe d^2 is internally screw-threaded, as at d^6 , and in said end is fitted one end of a water-conducting pipe D, which is screw-threaded externally, said pipe forming a handle by means of which the brush is manipulated.

Around the pipe D is a casing E, preferably of wood, which abuts against a flange d^7 , which extends around the end of the pipe d^2 , which receives the end of pipe D. The other 15 end of pipe D is also screw-threaded externally and is fitted within the internally-screw-threaded opening f of a check-valve F, said valve having a flange f' extending around the opening f and against which the casing E 20 abuts in the same manner as against the flange d^7 . The check-valve F, as seen in Fig. 4, is of the ordinary construction and is provided with an upper chamber f^2 and a lower chamber f^3 , separated by a diaphragm f^4 , the upper chamber communicating with the pipe D and the other chamber with the supply-pipe for the liquid. In the diaphragm f^4 is a valve f^5 , through which extends a plunger f^6 . In the bottom of the valve is a removable plug f^7 , and resting upon said plug is a spiral spring f^8 , which also extends around the plunger f^6 and bears also upon the under side of the valve f^5 . The upper end of plunger f^6 extends through the upper portion of the casing of valve F, through the nipple f^9 on the outer side portion of said casing, which nipple is screw-threaded externally. Upon said nipple is a packing-nut f^{10} . Upon the other end of the valve F is an internally-screw-threaded flange f^{12} . Upon said flange is a bearing-post g , with which post is pivotally connected one end of a lever G, which also bears upon the plunger f^6 and extends a considerable distance parallel with the casing E 45 of the pipe D. In the screw-threaded flange f^{12} of the valve F is inserted one end of a short length of pipe h, which is also screw-threaded externally at both ends. Over the other end of pipe h is fitted one end of a flexible pipe II.

I represents a tank for holding liquid and is arranged in position at a suitable elevation to give a pressure to the liquid. In the side of tank I, near the bottom, is a short pipe i, 55 with which is connected the other end of the flexible pipe II, leading from the handle D.

In the various uses to which the brush A is applied the handle E is seized, preferably in the left hand, about midway of the length of 60 said handle, the right hand grasping the outer end of the handle in close proximity to the lever G. When the flow of the liquid is desired, the lever G is forced downwardly toward the casing E of handle D, which 65 presses the plunger f^6 and the valve f^5 , and the liquid in pipe II, with the pressure afforded by the quantity in the tank I, flows

through the chamber f^3 in valve F into the chamber f^2 , through the valve-opening, and thence into the pipe or handle D, thence to 70 the conducting-pipe d^2 on the brush A and through the branch pipe d^3 and the adjustable telescopic pipe d to the respective pipes b b, and emerges in jets from the perforations b^x in each distributing-pipe and passes to the 75 interstices of the brush, and as the brush is used the liquid continues to flow into the brush and is spread by the bristles, the rapidity of the flow being at all times within the control of the operator and the valves partially or entirely closed at will.

In the employment of the brush I am enabled to apply various kinds of liquids for covering surfaces subject to the weather, and in which may be included lime washes or oil-paints. I intend, however, the special application of the brush to the washing of freshly-killed beeves, in which the removal of the grease from the flesh is met with difficulty. In such cases the scrubbing of the 90 flesh of the beeves may be accomplished with a steady flow of water and the operation completed in less time, and without grease adhering to the brush, than heretofore.

The invention is adapted to the washing of 95 carriages, windows, and other obvious uses in which a brush is employed, the pipes b b being readily adjusted to any width of brush in common use. For this purpose the nut d^4 is turned so as to release connection with the pipe d^2 and the pipe d drawn outwardly or thrust inwardly, as the width of brush requires.

When connected with a broom, my invention is modified and a pipe-frame employed, 105 as seen in Fig. 5, and in which form, instead of the separate perforate pipes b b, I employ an elliptical-shaped perforate pipe K, which is in one piece and extends around the fibrous portion of the broom I. Upon each side of 110 the fibrous portion of the broom are upwardly-extended pipes k k, which are short in length. In each pipe k k is telescoped the lower end portion of a pipe m, of smaller size than the pipe k, and in pipe k is a set-screw k², which 115 impinges against pipe m. The upper end portions of the pipe m m are bent nearly at right angles and toward each other and connected with the respective opposite sides of a pipe M, which forms the handle to the 120 broom. The lower end portion of the pipe M is closed a short distance below the point of connection of the pipes m m therewith, and between the closed portion of said handle M is a socket m', which receives a short portion 125 of an ordinary wood handle to the broom and so as to give a rigid connection with the handle M. The handle M at its outer end is connected with a valve F and tank in precisely the same manner as described of the handle 130 D, the liquid passing freely to the broom through the perforations k' in the liquid-distributing pipe K and these perforations given such a direction as to compel the entry of the

liquid within the interstices of the broom. In street service the tank I may be mounted upon wheels and the broom kept supplied with water, while in indoor use the water 5 may be obtained directly from the water-service pipe, with which the flexible pipe H may be readily connected.

In the modification shown in Fig. 6 a single distributing-pipe is employed, which extends 10 along one side of the brush and is bent at right angles and extended parallel with one end of said brush. The clamps *o* upon both sides of the brush are essentially the same as clamps *c c*. The upper ends of those clamps 15 which are connected with the distributing-pipe on one side of the brush are joined together by a handle or bar *o*³, extending from the upper end of one clamp to the upper end of the other clamp. The clamps upon the 20 other side of the brush bear directly upon the outer edge of the said side and are joined together by a handle, which is the same as handle *o*³. The clamps *o* are secured by clamping-bolts *o'*, which are the same as the clamping-bolts *c*². The pipe *N*, supplying the liquid 25 to the distributing-pipe, extends in the direction of the length of the brush, and at a point near the clamps *o o'*, in the direction of one end of the brush, the said pipe is bent 30 at right angles and thence over the edge of the brush and connected with the distributing-pipe. The valve *F*, controlling the flow

of water, is in the pipe *N* and near the brush, so that the lever *P* may be extended between the handles, and thus operated by a slight 35 pressure of the palm of the hand.

Having fully described my invention, what I now claim as new, and desire to secure by Letters Patent, is—

1. A liquid-supplying device for brushes and brooms comprising separate perforate liquid-distributing pipes adjustable telescopic liquid-conducting pipes connected with the separate liquid-distributing pipes respectively and having external screw-threads upon 45 one of said pipes and a joint-closing nut, and a hollow handle connected with the liquid-conducting pipe.

2. In a liquid-supplying device for brushes and brooms, the combination with separate 50 perforate liquid-distributing pipes, of clamping-plates upon each pipe, and a clamping-bolt connecting opposite clamping-plates and adjustable telescopic liquid-conducting pipes connected with the separate liquid-distributing pipes respectively, and having external screw-threads upon one of said pipes, and a joint-closing nut, and a hollow handle connected with the liquid-conducting pipe.
